UNITED STATES PATENT OFFICE.

GEORGE LORENZO LANE, OF WILLIAMSTOWN, WEST VIRGINIA.

WELL-DRILLING BIT.

1,218,671.

Specification of Letters Patent. Patented Mar. 13, 1917.

Application filed August 1, 1916. Serial No. 112,515.

To all whom it may concern:

Be it known that I, GEORGE L. LANE, a citizen of the United States, and a resident of Williamstown, in the county of Wood and State of West Virginia, have invented a new and Improved Well-Drilling Bit, of which the following is a full, clear, and exact description.

This invention relates to deep well rock drilling bits and has particular reference to the formation or design of the body of the drilling bit adapting it for reliability and effectiveness in practice.

Among the objects of the invention, therefore, is to so construct a drilling bit as to insure the greatest efficiency and durability of the tool and to reduce to a minimum the liability of the drill hole becoming crooked and that the bit will go through the casing and drill the hole large enough to allow the casing to follow.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a side elevation of my improved drilling bit;

Fig. 2 is a rear elevation;

Fig. 3 is a front elevation; and

Fig. 4 is a bottom plan view with a diagram to indicate the relation of the drilling bit to the drilled hole.

Referring now more particularly to the drawings, I show a drilling bit having a body 10 with a coupling nipple 11 and provided at its active end with a plurality of points, each having a web or wing structure supporting it.

One of the chief features of the novelty of this improvement lies in the center point 12 arranged precisely in the longitudinal axis of the tool and being bounded by three inclined facets 13, 14, and 15. The meeting line of each two adjacent facets is inclined upwardly from the point 12. The structure supporting the point 12 and its facets constitutes a main rib 16 of relatively heavy construction.

In addition to the parts just described, I provide two cutting points 17 and 18, each bound on its bottom by two facets 19 and 20. The meeting line for each pair of facets 19 and 20 for each point 17 or 18 is indicated at 21 and it inclines upwardly slightly where it intersects the other line 21 and the meeting line 22 between the facets 14 and 15 at the point 23. This point, it will be observed, is eccentric to the point 12 and longitudinal axis of the drilling bit.

I wish to point out particularly that the point 12 extends materially below the horizontal plane of the points 17 and 18, whereby the point 12 is given an effective lead serving to hold the tool for operation in a definite fixed line coinciding with the axis of the tool. The inclined facet 13 adjacent the point 12 serves to cause the points 17 and 18 to be crowded laterally, with respect to the center of the hole and cause an undercut effect of the tool, with respect to the cutting points 17 and 18. The point 17 is carried upon the lower end of a web 17^a while the other point 18 is carried on a similar web 18^a. These webs extend practically throughout the whole length of the body or rib 16 and make a rigid and strong tool.

As noted in Fig. 4, each of the ribs or webs is cylindrical in end view, the axis of the curvature thereof being substantially coincident with the point 23 where the line 22 intersects the lines 21. The edges, therefore, of the side points or cutting portions of the tool represented by the lines 24 and 25 produce a shearing effect on the side portions of the hole formed through the rock. The cutting edge and point portions of the webs 17^a and 18^a project radially somewhat beyond the main surfaces of these parts.

I claim:

1. The herein described drilling bit comprising a main central rib having a leading point at its lower end in alignment with the axis of the rib and drill, said point being formed by the intersection of three triangular facets, said drill also including two other web members, each having a cutting point at its lower end projecting radially outwardly beyond the main surface of such web and each of said lateral points being bounded by two inclined facets, one of the facets of the leading point structure being inclined upwardly and serving to force the other two cutting points outwardly with re-

spect to the axis of the hole being drilled, all of the other facets meeting at a point eccentric to the axis of the tool and leading point.

2. The herein described rock drilling bit comprising a straight, strong, rigid body terminating in a pyramidal downwardly projecting point, the apex or point proper being in the axis of the body and vertical center of the hole to be drilled, and a pair of parallel rigid webs of less width than the main body projecting outwardly from the

main body, each of said webs having at its lower end an outwardly flared cutting point serving to form an undercut effect in the operation of the tool, each of the latter mentioned cutting points being effective at the periphery of the tool while the point first mentioned is effective in the center of the hole and projects materially below the horizontal plane of the two side points.
